(57) **CLAIM**

The ornamental design for a dental guard, as shown and described.

DESCRIPTION

FIG. 1 is a top front left side perspective view of a dental guard showing my new design.

FIG. 2 is a bottom front left side perspective view of the dental guard as shown in FIG. 1 showing my new design.

FIG. 3 is a top rear left side perspective view of the dental guard as shown in FIG. 1 showing my new design.

FIG. 4 is a bottom front perspective view of the dental guard as shown in FIG. 1 showing my new design.

FIG. 5 is a top front perspective view of the dental guard as shown in FIG. 1 showing my new design.

FIG. 6 is a front elevation view of the dental guard as shown in FIG. 1 showing my new design.

FIG. 7 is a rear elevation view of the dental guard as shown in FIG. 1 showing my new design.

FIG. 8 is a right side elevation view of the dental guard as shown in FIG. 1 showing my new design.

FIG. 9 is a left side elevation view of the dental guard as shown in FIG. 1 showing my new design.

FIG. 10 is a top plan view of the dental guard as shown in FIG. 1 showing my new design; and,

FIG. 11 is a bottom plan view of the dental guard as shown in FIG. 1 showing my new design.
